United States Patent Office.

JAMES P. TYSON, OF PHILADELPHIA, PENNSYLVANIA.

Letters Patent No. 75,711, dated March 17, 1868.

IMPROVEMENT IN CARRIAGE-THILL.

The Schedule referred to in these Letters Patent and making part of the same.

TO ALL WHOM IT MAY CONCERN:

Be it known that I, JAMES P. TYSON, of Philadelphia, Pennsylvania, have invented an Improved Carriage-Thill; and I do hereby declare the following to be a full, clear, and exact description of the same.

My invention consists of a tapering strip of gum-elastic, or its equivalent, applied to a carriage-thill, as fully described hereafter, so as to be retained securely in its place, and so that the parts of the thill, when connected, are free from all disagreeable rattling.

In order to enable others skilled in the art to make and apply my invention, I will now proceed to describe its construction and operation, reference being had to the accompanying drawing, which forms a part of this specification, and in which—

Figure 1 is a perspective view of my improved carriage-thill, showing the manner of connecting the two parts.

Figure 2, a sectional elevation, with the parts in the same relative position.

Figure 3, the same, showing the parts of the thill as they appear when connected together; and

Figure 4, a front view, with the parts detached from each other.

A represents a metal coupling-block, which is secured to the clip or axle of a carriage in the usual manner, and which has extending through it, from one side to the other, a circular opening, *a*. Communicating with this opening, and at the rear of the same, is a vertical opening, *b*, of square or other convenient form, for a purpose described hereafter, and the front of the block is divided into two projecting portions, *c* and *c'*, by a recess, *d*, which also communicates with the circular opening *a*, (see fig. 1,) and with the vertical opening *b*. The usual metal bar *B* is secured to each of the shafts of a carriage, and has at its inner end *e* a pin, *f*, which projects on each side of the said bar to a distance equal to the width of the coupling-block *A*, as shown in fig. 4.

In order to connect the shafts to the coupling-blocks they must be elevated, as shown in figs. 1 and 4, and so held that each of the pins *f* shall be at one side of and opposite to the circular openings *a* of the coupling-blocks. The pins *f* are inserted into these openings by moving the shafts laterally, and the latter are thus moved until the pins are contained entirely within the circular openings, and until the bars *B* are opposite to the recesses *d* of their respective coupling-blocks, (see fig. 2.) The shafts are then partially lowered, and thereby turned upon the pins *f* as a centre, to about the position shown in dotted lines, fig. 2, or until the shoulders *h* of each of the bars are clear of the vertical openings *b*, the bars entering the recesses *d* formed for their reception in the blocks, as shown in the drawing. A tapering or wedge-shaped strip, *C*, fig. 3, of gutta percha or rubber, is then inserted into the lower end of each of the openings *b*, and drawn upwards until it is bound tightly between the block and pin *f*. Its thin end is then drawn over and attached to the bar *B* by suitable bands *i i*, after which the bar is lowered to the position shown in fig. 3. In thus lowering the bar, the strip *C* is drawn upwards, and a thicker portion caused to bear against the pin *f*, the latter being thus held tightly in its bearing, and all disagreeable rattling prevented.

When the two parts of the thill are connected as above described, the shafts can be raised or lowered to any required extent without danger of disconnecting them, and it will be impossible to disconnect the thill by jolting, as the projecting portions *c* and *c'* of the block effectually prevent all lateral motion until the shafts are elevated to the proper vertical position, nor can the pin *f* rise vertically from its bearing, as the open space *x* above the latter is only sufficiently wide to permit the passage of the narrowest portion *z* of the bar.

It will be evident from the above that my improved thill is as applicable to vehicles having a single pole as to those in which the double shafts are employed.

I claim as my invention, and desire to secure by Letters Patent—

A tapering strip, *C*, of gum-elastic, or its equivalent, secured at one end to the bar *B*, and extending between the end of the latter and the coupling-block, substantially as and for the purpose described.

In testimony whereof, I have signed my name to this specification in the presence of two subscribing witnesses.

JAMES P. TYSON.
